J. REED.
MACHINE FOR ROLLING IRON, &c.

Patented July 15, 1802.

July 15, 1802

Gales Patent. Date July 15, 1802.

The invention referred to in this Gales Patent and making part of the same containing a description in the words of the said Sept. 16, 1802 himself of his improvement showing a method of rolling iron or other metal for the purpose of making Nails. Description or specification of Sept. 16, 1802's invention: method of rolling iron or other metal for the purpose of making Nails to wit. It consists of suitable rollers the surface of one or both of which is indented or made uneven which rollers are informed and used in the common way of --- mills for rolling iron or otherwise. The rollers or rollers being more or less indented or made uneven in such a manner as to give the impression required according to the proportions to which the nails are designed to be brought on rolling and according to their size, length and kind, whether joining head to head or head to point and with or without perfect heads after being slit and separated. By which method bars, sheets or plates of iron or copper or other metal, may be rolled drawn and milled into plates of different and of uneven thickness which when slit produce rods shaped into nails joining end to end to be afterwards separated and headed if not done on the mill; and in this way by reason of the indenting or unevenness of the rollers nails and spikes of all sizes may be formed.
